FOREIGN PATENT DOCUMENTS

WO 9743980 11/1997

Primary Examiner — Zenia I Bennett(74) *Attorney, Agent, or Firm* — Michael Best &
Friedrich LLP(57) **CLAIM**

We claim the ornamental design for a flosser pick, as shown.

DESCRIPTION

FIG. 1 is a perspective view of a flosser pick of the present invention.

FIG. 2 is a front view of the flosser pick of FIG. 1.

FIG. 3 is a rear view of the flosser pick of FIG. 1.

FIG. 4 is a left-side view of the flosser pick of FIG. 1.

FIG. 5 is a right-side view of the flosser pick of FIG. 1.

FIG. 6 is a top view of the flosser pick of FIG. 1; and,

FIG. 7 is a bottom view of the flosser pick of FIG. 1.

The broken lines depicting portion of the flosser pick in the drawing are for illustrative purposes only and form no part of the claimed design.
